UNITED STATES PATENT OFFICE.

WILLIAM A. GEIGER, OF CHICAGO, ILLINOIS, ASSIGNOR TO W. H. MINER, INC., OF CHICAGO, ILLINOIS, A CORPORATION OF DELAWARE.

DOOR-OPERATING MECHANISM.

Application filed May 20, 1926. Serial No. 110,434.

This invention relates to door operating mechanisms.

One object of the invention is to provide a simple and efficient door operating mechanism for forcing the door when partly closed to tightly closed position, for holding the door closed, and for forcing the same open to facilitate the complete opening thereof.

Another object of the invention is to provide a door operating mechanism especially adapted for pivoted doors of refrigerator cars, including operating mechanism movably mounted upon one of said doors, the ends of said mechanism being arranged to project beyond the edges of the door and cooperate with keeper means arranged in such manner as to permit movement of the ends of said operating mechanism continuously in one direction, or the other, for effecting both opening and closing movements of the door, or to permit opening and closing movements of the door to be effected by movement of the operating mechanism first in one direction and then in the opposite direction in a plurality of positions.

Other and further objects of the invention will more fully and clearly appear from the description and claims hereinafter following.

In the drawings forming a part of the specification, Fig. 1 is a side elevational view of a portion of a refrigerator car showing my improvements in connection therewith. Fig. 2 is a vertical, sectional view, on an enlarged scale, partly broken away, corresponding substantially to the line 2—2 of Fig. 1, showing the position of the parts of the mechanism when the door is tightly closed. Fig. 3 is a horizontal sectional view on an enlarged scale of the lower end of the operating mechanism taken on line 3—3 of Fig. 2, and showing the same in engagement with the lower keeper shown in top plan, the door in partly open position being shown in dotted lines. Fig. 4 is a fragmentary side elevation of refrigerator car doors, similar to Fig. 1, but on a reduced scale, showing a different embodiment of the invention. And Fig. 5 is a vertical, sectional view, on an enlarged scale, partly broken away, corresponding substantially to the line 5—5 of Fig. 4.

Referring first to Figs. 1 to 3 inclusive,

the side of the car is shown as provided with a door frame 10 and two pivoted doors 11 and 12. The doors have the usual beveled meeting edges, and the customary insulation or packing is employed between the free edges of the doors and between the door and door frame. The doors 11 and 12 are mounted for swinging movement about vertical axes, being supported by suitable hinges 13—13.

The door operating mechanism comprises broadly an operating bar A; keepers B—B; and actuating mechanism C.

The operating bar A preferably is in the form of a flat elongated member tapering from an intermediate portion towards its opposite ends, and being of a length somewhat greater than the vertical height of the door 12, said bar being pivotally mounted at a central point as indicated at 14, so that the opposite ends of said bar swing in a direction substantially parallel of the plane of the door 12, movement of the end portions being limited and guided by means of suitable guide brackets 15—15. Each end portion of the bar A is reduced as indicated at 16 and upon said reduced portion there is mounted an anti-friction element 17.

The keepers B—B are two in number, one of the same being secured to the door frame 10, adjacent the top edge of the door 12, while the other keeper is secured to the door frame 10 adjacent the bottom edge of the door 12. The bottom keeper B is preferably in the form of a casting having a bottom wall 18, and upstanding portions providing a rear wall 19, extending substantially parallel to the plane of the door frame, the wall 19 merging into outwardly inclined oppositely extending walls 20 and 21, and spaced outwardly from walls 19, 20, and 21, is an upstanding abutment 22 provided with outwardly inclined oppositely disposed walls 23 and 24, the walls 23 and 24 being connected by a flat portion 25. The walls 23 and 24 extend substantially parallel with the walls 21 and 20, and in conjunction with the flat portion 25 and back wall 19 define a double ended cam slot adapted for the reception of the anti-friction element 17 on the end of the bar A, said end being adapted to traverse the cam slot throughout its extent. The lower keeper B is provided with flanges 26 and 27, through which are extended securing bolts 28—28 for rigidly mounting the

keeper B upon the door frame. The flange 27 of the keeper B is extended to the left, as best shown in Fig. 1, and is provided at its end with a pivoted latch 29 adapted to 5 cooperate with a wear plate 30 mounted upon the lower right hand corner of the door 11.

The upper keeper B is identically similar to the lower keeper B, except for its opposite disposition and the omission of the extension upon the flange 27, and similar parts of the two keepers will be indicated by similar reference characters. The upper keeper B provides a double ended cam slot for the 10 reception of the upper end of the bar A in the same manner as provided in connection with the lower end of the bar in the lower keeper.

The actuating means C comprise a lever 20 31 pivoted adjacent one end as indicated at 32, so as to provide a handle 33 and crank portion 34. The crank portion of the lever 31 is pivotally connected by a link 35 with the bar A, the construction being such that 25 the swinging movement of the handle 31 of the lever effects corresponding swinging movement of the opposite ends of the operating bar A.

The crank portion 34 of the lever extends 30 somewhat beyond the pivotal connection with link 35 therewith and is provided with an aperture adapted to cooperate with a locking bracket 36, said locking bracket and crank portion 34 being provided with apertures 35 adapted to register to permit the insertion of a sealing member in the usual manner.

In operation, assuming the door 12 to be 40 in its fully closed position as shown in full lines in Fig. 1, and it is desired to open said door, the lever 31 may be swung in a counter clockwise direction as shown on dotted line in Fig. 1, which imparts movement to the opposite ends of the operating bar in a clockwise direction, thus causing the end portions 45 of the operating bar to bear against the wall 20 of the lower keeper, and the wall 21 of the upper keeper, which moves the door 12 in an outward direction a sufficient distance 50 to clear the insulation, after which the door 12 may be swung to fully open position. If instead of swinging the operating lever 31 in a counter clockwise direction, when the door is closed, conditions are encountered 55 which might render clockwise swinging of the lever 31 and of the bar more convenient, said lever may be swung in a clockwise direction, effecting counter clockwise movement of the opposite ends of the operating bar A. 60 During this movement, the lower end of the operating bar will bear upon the wall 21, while the upper end of the operating bar will bear upon the wall 20, in this way also effecting movement of the door 12 in an opening direction. After the door 12 has

been opened sufficiently to clear the insulation in either manner above referred to, the same then may be easily swung to fully open position, and the latch 29 disengaged from the wear plate, permitting the door 11 also 70 to be readily swung to fully opened position.

When it is desired to close the doors, the door 11 is swung to nearly closed position, after which the door 12 is swung into position so that the opposite ends of the bar A 75 may be engaged with the keepers in either of the two positions. If it is thought to be more convenient to swing the lever 31 in a clockwise direction, the upper and lower ends of the bar are engaged with the cam 80 surfaces 23 and 24 respectively of the upper and lower keepers, bearing thereon during movement of the operating bar so as to effect closing movement of the door. If on the other hand, counter clockwise rotation of the 85 lever 31 is desirable, the upper and lower ends of the bar may be engaged with the inclined walls 24 and 23 of the upper and lower keepers, traverses of the ends of the bars in the manner described moving the door to 90 fully closed position. After the door 12 has been closed, the latch 29 may be turned into position to hold the door 11 closed. It should be observed that movement of the lever 31, and consequently of the bar A, continuously 95 in one or the other of two directions will effect both opening and closing movements of the door when operation of this character is desired.

Referring now to Figs. 4 and 5 a somewhat different embodiment of the invention 100 is contemplated. In this construction, a vertically reciprocable operating bar E is provided, which is mounted for reciprocation upon the door 37 by means of guide brackets 105 38-38. The bar E is of somewhat greater length than the vertical height of the door 37 and is provided at its opposite ends with lateral extensions forming T-shaped heads 39 and 40.

Keepers F-F are provided, one of said keepers being secured to the frame 41 adjacent the upper edge of the door 37, while the lower keeper F is secured to the frame 41 adjacent the lower edge of the door 37. The lower keeper is provided with side portions 42-42, said portions being spaced apart, and arranged to provide oppositely inclined cam surfaces 43, 44, 45 and 46, said cam surfaces defining a continuous cam slot in each of the side portions 42 for the reception of the lateral extensions which form the T-head on the lower end of the bar E. The lower keeper F is provided with flanges 47 and 48 through which are extended securing bolts, 125 the flange 48 being extended to the left, as shown, and provided with a pivoted latch 49 adapted to engage the wear plate 50 on the lower right hand corner of the door 51. The upper keeper F is identically similar to 130

the lower keeper, except for the omission of the extension on the flange 48 of the lower keeper, and the various parts of said keeper will be designated by reference characters 5 similar to those utilized in connection with the lower keeper. Reciprocation of the bar E is effected by means of a lever 52 pivotally mounted upon the door 37 as indicated at 10 53 and having a slotted connection with the bar E as indicated at 54.

In operation, assuming the door to be closed as shown in the drawings, when it is desired to open the door, the lever 52 is 15 swung in a clockwise direction effecting vertical reciprocation upwardly of the bar E, causing traverse by the lateral extensions of the opposite ends of the bar E of the cam surfaces 45 of the upper and lower keepers resulting in opening movement of the door. 20 If desired, the bar E may be reciprocated downwardly causing traverse of the cam surfaces 46 by the lateral extensions forming the T-heads of the opposite ends of the bar E, which also results in moving the door 25 in an opening direction. When the door 37 has been moved sufficiently to clear the insulation about the operating mechanism, said door may be readily swung to fully opened position, after which the latch 49 30 may be swung to inoperative position, and the door 51 fully opened. When it is desired to close the doors, the door 51 is swung nearly closed, after which the door 37 is 35 swung toward closed position until the T-heads of the bar E are in position to enter the cam slots of the keepers, and the door may be forced to closed position, either by reciprocating the bar E upwardly or downwardly as most convenient to cause 40 traverse of the cam surfaces 43 or 44 respectively. After the door 37 is closed, the latch 49 may be swung to operative position to hold the door 51 in closed position.

While I have herein shown and described 45 what I now consider the preferred manner of carrying out my invention, the same is merely illustrative and I contemplate all changes and modifications that come within the scope of the claims appended hereto.

50 I claim:

1. In a door operating mechanism, the combination with a door frame and a pivoted door; of a movable operating member mounted on said door; and keeper means 55 mounted on said frame and adapted to co-act with said operating member, said keeper means being provided with a guide means for said operating member, including a plurality of successively acting cam surfaces adapted to co-act with said operating member in successive positions thereof for effective successively closing and opening of said door.

2. In a door operating mechanism of the 60 character described, the combination with

a frame providing a door opening, and a door cooperating with said frame; of a single operating member movably mounted on said door having the end portions thereof projecting beyond the opposite edges of 70 said door, and keeper means mounted on said door adjacent said end portions, said keeper means being provided with oppositely disposed cam surfaces inclined outwardly from said door frame and adapted 75 to co-act with the end portions of said operating member to effect movement of said door in opening and closing directions.

3. In a door operating mechanism of the character described, the combination with 80 a frame providing a door opening, and a door cooperating with said frame; of a single operating member movably mounted on said door having the end portions thereof projecting beyond the opposite edges of 85 said door, and keeper means mounted on said door adjacent said end portions, said keeper means being provided with oppositely disposed cam surfaces inclined outwardly from said door frame and adapted to co-act 90 with the end portions of said operating member to effect movement of said door in opening and closing directions, said cam surfaces being connected at the points where the same converge to provide con- 95 tinuous cam surfaces for said keeper.

4. In a door operating mechanism, the combination with a door frame and a door; of an operating member movably mounted 100 upon said door; and keeper means mounted on said door frame, said keeper means being provided with cam surfaces arranged at an angle to each other and defining a cam slot having a plurality of openings in different positions, each of which is arranged to permit the entrance of said operating member to said cam slot; and means for moving said operating member to effect 105 traverse by the same of said keeper means.

5. As an article of manufacture, a keeper 110 provided with spaced walls defining a continuous cam slot having a rectilinearly extending central portion and end portions disposed at an angle to said central portion and diverging outwardly therefrom. 115

6. As an article of manufacture, a keeper having spaced substantially parallel walls extending at a certain angle, and other spaced substantially parallel walls extending at an angle to said first mentioned walls, 120 said walls defining cam slots for co-operation with an operating member, said slots having independent openings for the entrance and withdrawal of the operating member with respect to said keeper. 125

7. In a door operating mechanism of the character described, the combination with a door frame and a pivoted door; of an operating member pivotally mounted on said door intermediate its ends, said member hav- 130

ing actuating elements extending beyond opposite edges of said door; keeper means mounted on said door frame and adapted to cooperate with the end elements of said 5 operating member, each of said keepers being provided with a continuous cam slot, one portion of which is disposed at an angle to another portion thereof, said slot being arranged for the reception of the end parts 10 of said operating member to cause traverse of either portion of said cam slot; and means for imparting operating movements to said operating member.

8. As an article of manufacture, a keeper 15 having spaced walls defining cam slots, one portion of said keeper having the spaced walls disposed at an angle to the spaced walls of another portion of said keeper, said cam slots communicating with each other 20 at their inner ends, and each slot having a separate opening at its outer extremity adapted for the entrance and withdrawal of an operating member.

9. In a door operating mechanism, the 25 combination with a door frame and a pivoted door; an operating member movably mounted on said door; and keeper means mounted on said door frame and adapted to co-act with said operating member, said 30 keeper means being provided with a plu-

rality of oppositely inclined cam surfaces defining cam slots communicating at their inner ends, and providing openings at their outer ends, said cam slots being formed to permit traverse of said operating member 35 from engagement with one to engagement with the other without withdrawal of said operating member from said keeper, to effect movement of said door in opening and closing directions.

10. In a door operating mechanism, the combination with a door frame and a pivoted door; of keeper means mounted on said door frame; an operating member movably mounted on said door; keeper engaging means on said operating member and movable therewith, said keeper means being provided with a guideway having communicating guide portions extending in opposite directions and inclined outwardly away 45 from said door frame and cooperating with said engaging means, whereby movement of the operating member in one direction through both guide portions effects successively closing and opening movements of 50 the door.

In witness that I claim the foregoing I have hereunto subscribed my name this 14th day of May, 1926.

WILLIAM A. GEIGER.
